[57] **CLAIM**

The ornamental design for the bookmark, as shown and described.

DESCRIPTION

FIG. 1 is a top perspective view of a bookmark showing my new design with a book shown in broken lines for illustrative purposes only, forming no part of the claimed design;

FIG. 2 is a front elevational view of the bookmark in FIG. 1;

FIG. 3 is a left side elevational view thereof;

FIG. 4 is a rear elevational view thereof;

FIG. 5 is a right side elevational view thereof;

FIG. 6 is a top plan view thereof;

FIG. 7 is a bottom plan view thereof;

FIG. 8 is a top perspective view of a second embodiment showing my new design with a book shown in broken lines for illustrative purposes only, forming no part of the claimed design;

FIG. 9 is a front elevational view of the bookmark in FIG. 8;

FIG. 10 is a rear elevational view thereof;

FIG. 11 is a left side elevational view thereof;

FIG. 12 is a right side elevational view thereof;

FIG. 13 is a top plan view thereof; and

FIG. 14 is a bottom plan view thereof.

FIG. 1.

FIG.4.

FIG.3.

FIG.2.

FIG.5.

FIG.6.

FIG.7.
